PLASTIC SHEET MATERIAL

Shep Silverman, Massapequa Park, N.Y., assignor to
Southbridge Plastic Co. Inc., New York, N.Y., a corporation

Filed Jan. 3, 1960, Ser. No. 63,427

Term of patent 3½ years

(Cl. D87—3)

The figure is a plan view of a plastic sheet material, showing my new design.

The dot and dash lines on the drawing outline a design unit, which unit is repeated in regular succession, as indicated by the extensions beyond the unit boundary.

I claim:

The ornamental design for a plastic sheet material, substantially as shown, and described.
